ATTORNEY.

UNITED STATES PATENT OFFICE

LESTER L. BLANCHARD, OF DOVER-FOXCROFT, MAINE, ASSIGNOR TO HENRI CREPEAU,
OF MONTREAL, CANADA

CHIMNEY

Application filed July 26, 1929. Serial No. 381,341.

This invention relates to chimneys, and more particularly to devices mounted on the outlet portion thereof.

The object of the invention is to provide means whereby the efficiency of the chimney is greatly increased.

A further object is to provide means whereby the up draft is accelerated and the formation of smoke is greatly reduced.

10 A further object is to protect the outlet of the chimney from injurious effects due to flue gases, rain, snow and ice, and to prevent condensation therein and deposits thereon.

Further objects will be set forth hereinafter. 15 The invention consists briefly of a lining member of heat absorbing and heat retaining material, mounted within the outlet of the chimney.

Reference is made to the accompanying drawings in which:

Figure 1 is a sectional view through a brick chimney top with outlet device mounted thereon.

20 Figure 2 is a similar view of a metal flue with the device mounted thereon.

The chimney 1 which may be constructed of any suitable material, is provided at its outlet with a lining member 2 which extends downwards into the flue a suitable distance 25 according to the size of the chimney.

This lining member 2 is composed of a material which is heat absorbing and heat retaining, such for example as glass wool.

This lining member 2 is formed to have its 30 inner surface tapered upwardly, whereby the size of the flue is gradually reduced to the outlet.

The inner surface of the lining member 2 in most cases is covered by a casing 3. This 35 casing 3 may be made of non-corrodible sheet metal.

The outer surface of the lining member 2 which is in contact with the inner surface 10 of the chimney 1, may have a covering of 40 asbestos board or other suitable material in order to retain the member 2 in shape, if it consists of loose or non-solid material.

The upper end of the member 2 has a conical extremity projecting above the chimney. 45 This is preferably covered by a metal

cap 30 connected to the top edge of the casing 3, which inclines outwardly to the outer edge of the chimney 1, and this cap 3 is usually provided with a dependent flange 31 which fits around the chimney top. 55

In Figure 1 the top of the chimney is shown squared, and a space 5 beneath the cap 30 occurs. This space 5 may be filled up with cement or the like, to assist in providing a firm and secure setting for the device when 60 installed on the chimney.

Means are provided to seal the lower edge of the member or its casing to the inner surface of the flue, in order to prevent the entrance of gas or moisture between the chimney 1 and the lining member 2. 65

The method of mounting the lining member 2 and of retaining it in position, may be varied in order to suit the different shapes of chimneys and the particular conditions in each application, without going beyond the scope of this invention. 70

With the invention constructed as above set forth or on similar lines, its operation is 75 as follows:—

The heated gases arising from the combustion area below the chimney, on reaching the lining member will give up a large amount of their heat to it. When the member becomes heated, it creates an increased up draft in the flue, and the combustion of the fuel in the combustion chamber will be more complete, with the result that the percentage of CO_2 in the flue gases will be increased, while the percentage of CO which escapes 80 from the combustion zone will be reduced to a minimum. 85

This increased up draft in the outlet prevents cold air from passing downwards in 90 the chimney top and cooling the combustion gases therein, and thereby producing smoke.

The heated outlet further prevents the condensation of moist gases and the deposit of matter such as creosote on the flue wall. 95

The confined area of the outlet also reduces the amount of rain or snow that can enter the chimney to a minimum.

The cap or top of the member, which will 100 also become heated will keep its surface clear of any accumulation of snow or ice.

By means of the sealed lower edge of the device, flue gases will be prevented from penetrating between the flue wall and the outer surface of the lining member, and the wall will thus be preserved from the injurious effects of such gases.

By increasing the chimney draft and preventing back draft and the chilling of the combustion gases, great economy in fuel consumption will be secured.

Expense charges for upkeep, cleaning and repairs will be thereby reduced to a minimum.

What I claim is:—

1. In a chimney outlet device, a lining member of heat absorbing and heat retaining material, tapered upwardly, and mounted in the outlet of the chimney and secured thereto by metallic means.

2. In a chimney outlet device, a lining member of heat absorbing and heat retaining material, tapered upwardly and having a conical extremity projecting above the chimney, mounted in the outlet of the chimney and secured thereto by metallic means.

3. In a chimney outlet device, a lining member of heat absorbing and heat retaining material, tapered upwardly and having a sheet metal casing on its inner surface, mounted in the outlet of the chimney.

4. In a chimney outlet device, a lining member of heat absorbing and heat retaining material, tapered upwardly, having a sheet metal casing on its inner surface, with an outwardly inclined cap extending from its upper edge, mounted at the outlet of the chimney.

5. In a chimney outlet device, a lining member of heat absorbing and heat retaining material, tapered upwardly, having a sheet metal casing on its inner surface, with an outwardly inclined cap extending from its upper edge, having a dependent flange fitting around the chimney top, mounted at the outlet of the chimney.

6. In a chimney outlet device, a lining member of heat absorbing and heat retaining material, tapered upwardly and mounted in the outlet of the chimney, metallic means to secure the lining member in position and having a sealed contact with the flue wall at its lower edge.

LESTER L. BLANCHARD.
